OTHER PUBLICATIONS

Portion Package For Pourable Food Products, RD 414041, Oct. 1998, Research Disclosure Journal, ISSN 0374-4353.*Primary Examiner*—T. Chase Nelson*Assistant Examiner*—Karen Acker(74) *Attorney, Agent, or Firm*—Hasse & Nesbitt LLC; Donald E. Hasse(57) **CLAIM**

I claim the ornamental design for a carton, as shown and described.

DESCRIPTION

FIG. 1 is a top perspective view of the carton.

FIG. 2 is a bottom perspective view of the carton.

FIG. 3 is a front elevational view of the carton.

FIG. 4 is a back elevational view of the carton.

FIG. 5 is a left side elevational view of the carton.

FIG. 6 is a right side elevational view of the carton.

FIG. 7 is a top plan view of the carton.

FIG. 8 is a bottom plan view of the carton; and,

FIG. 9 is a sectional plan view of the carton taken along line 9—9 of FIG. 1.

The broken lines shown in the drawings are for illustrative purposes only and form no part of the claimed design.
